[57] **CLAIM**

The ornamental design for a tree pruner hook, as shown and described.

DESCRIPTION

FIG. 1 is a front elevational view of a tree pruner hook showing my new design;
FIG. 2 is a left end elevational view thereof;
FIG. 3 is an opposite end elevational view thereof;
FIG. 4 is a rear elevational view thereof;
FIG. 5 is a bottom plan view thereof;
FIG. 6 is a top plan view thereof; and,
FIG. 7 is a front elevational view thereof with the broken line showing of associated articles of the tree pruner being for illustrative purposes only and forming no part of the claimed design.
